UNITED STATES PATENT OFFICE.

BURR B. FREER, OF OIL CITY, PENNSYLVANIA.

STEAM-BOILER STAY-BOLT PLUG.

1,172,350.

Specification of Letters Patent. Patented Feb. 22, 1916.

Application filed February 3, 1915. Serial No. 5,873.

To all whom it may concern:

Be it known that I, BURR B. FREER, a citizen of the United States, residing at Oil City, in the county of Venango and State 5 of Pennsylvania, have invented new and useful Improvements in Steam-Boiler Stay-Bolt Plugs, of which the following is a specification:

My invention relates to steam-boilers of 10 the water-tube type, and more particularly to the sub-type thereof having the ends of the water-tubes communicating with water-legs.

It is the object of my invention to provide 15 the hollow stay-bolts for the sides of the water-legs with preferably non-corrosive metal plugs to prevent the air from short-circuiting the fire grate or burners beneath the water-tubes.

20 Referring to the accompanying drawing, Figure 1 is an elevation, partly in section, of a portion of a steam-boiler; Fig. 2, an enlarged view showing a portion of a stay-bolt in one wall of a water-leg, and one of my 25 plugs in the stay-bolt; Fig. 3, a side elevation, partly in section, showing the preferred form of my stay-bolt plug; and Fig. 4, an end view of a portion of the outer wall 30 of a water-leg with one of my plugs in a stay-bolt.

On the drawing, 1 designates a horizontal boiler, only one end portion thereof being shown.

2 is a water-leg secured to the under side 35 of the boiler 1 and provided with the opposite nearly vertical side-walls 3 and 4, and the end-walls 5 and 6.

7 and 8 are the water-tubes which have 40 their ends secured in the inner wall 4 and opening into the water-leg 2. The walls 3 and 4 are tied together by numerous hollow stay-bolts, only one, marked 9, being shown. The stay-bolts are threaded externally and 45 screwed into the walls 3 and 4 whereby the walls 3 and 4 are prevented from changing their relative positions, such as spreading.

If the stay-bolts have their central, or 50 axial, openings left open, considerable air will pass through them instead of going through the usual fire-grate or burners beneath the water-tubes. To prevent the air from short-circuiting or by-passing the grate or burners, I provide for each stay-bolt the 55 plug comprising the closure member 10 and the closure retaining and operating member

11. The member 10 is preferably tapered on one face, marked 12, and plane on the opposite face, marked 13. The member 11 is composed of preferably a single piece of resilient wire which I prefer to make of brass or other non-corrosive substance. The member 11 has its central portion bent back on itself to form the loop 14. The free ends of the member 11 form legs 15 which lie one over the other and are spread apart so that they will simultaneously engage diametrically opposite portions of the interior wall of the axial opening 16 in the stay-bolt and to exert sufficient pressure on the said wall to prevent the member 10, which is carried 65 by the intermediate portion 17 of the member 11, from moving from its normal position, which is shown on Figs. 1 and 2. The said intermediate portion of the member 11 extends entirely through the member 10, the 70 loop 14 extending beyond the plane face 13 and the legs 15 extending beyond the conical face 12. The legs 15 of the member 11 have considerable portions thereof lying 75 parallel, or in contact, with the wall of the stay-bolt opening 16 so as to hold the member 11 in line with the stay-bolt and the member 10 in close contact with the outer end of the stay-bolt with the conical face 12 80 projecting for some distance into the said 85 opening. In order to facilitate the entrance of the member 11 into the opening 16, I make the ends of the legs 15 inclined toward each other as shown at 17.

I prefer that the two members 10 and 11 90 shall be made of such material as will not rust or corrode in the stay-bolt and thereby prevent the ready removal of the plug. For example, the member 10 may be made 95 of Babbitt metal or lead, and the member 11 of brass or bronze. The loop 14 provides a convenient piece which the fingers may grasp or an extracting tool may be applied. I do not limit myself to the definite shapes 100 of the members 10 and 11 shown on the drawings.

I claim:

1. In a steam-boiler, a stay-bolt with an opening throughout its length, a closure for the opening, and a retaining member extending through the closure and having at one end a resilient portion in engagement with the wall of the opening and at the other end a suitable finger piece. 105

2. In a steam-boiler, a stay-bolt with an 110

- opening throughout its length, a non-corrosive closure for the opening, and a non-corrosive retaining member extending through the closure and having at one end a resilient portion in engagement with the wall of the opening and at the other end a suitable finger piece.
3. In a steam-boiler, a stay-bolt with an opening throughout its length, a closure for the opening, and a retaining member extending through the closure and having at one end a resilient portion in engagement with the wall of the opening and at the other end a suitable finger piece, the resilient portion of the retaining member contacting with the wall of the said opening for such
- 10
- 15

distance as to prevent the closure from moving downwardly.

4. In a steam-boiler, a stay-bolt with an opening throughout its length, a stopper for the opening, and a retaining member extending through the closure, rigidly connected to the stopper and having at one end a resilient portion in engagement with the wall of the opening.

²⁵
Signed at Pittsburgh, Pa., this 28th day of January, A. D. 1915.

BURR B. FREER.
